UNITED STATES PATENT OFFICE

LOUIS W. GREVE, OF CLEVELAND, OHIO, ASSIGNOR TO THE CLEVELAND ROCK DRILL COMPANY, OF CLEVELAND, OHIO

ROCK DRILL

Application filed May 24, 1928. Serial No. 280,189.

The present invention is directed to improvements in rock drills.

The primary object of the invention is to provide novel means for advancing the drill 5 to its work, the construction being adaptable to that type of drills known as stopers.

Another object of the invention is to provide simple and efficient means for cutting off the pressure fluid to the feed cylinder 10 without stopping the action of the piston hammer.

Another object of the invention is to provide means whereby the pressure fluid in the feed cylinder can be varied without effecting 15 the pressure in the piston hammer cylinder.

With these and other objects in view, as will appear as the description proceeds, the invention accordingly consists in the novel 20 features of construction, combination of elements, and arrangement of parts, hereinafter to be fully described and pointed out in the appended claims.

In the accompanying drawing, in which 25 similar characters of reference denote like and corresponding parts throughout several views:

Figure 1 is a longitudinal sectional view.

Figure 2 is a similar view of a modified 30 form.

Figure 3 is a fragmentary side view.

Referring to the drawing, 1 designates the cylinder in which is operable the piston hammer 2, reciprocatory movement being imparted to said hammer by pressure fluid flowing 35 from the pocket 3 in the head block 4, such fluid entering the pocket through the port 5. A valve seat 6 is formed in the head block and rotatable therein is a throttle valve 40 7 of conventional form, which is operable to control the flow of pressure fluid to the pocket. The head block has a passage 8 formed longitudinally therein which leads from the valve seat 6 and communicates with the lateral passage 9 formed with a tapered seat 45 10. The seat 10 opens into a chamber 11 in which is movable the stem of the needle valve 12, said valve including a shank 13 threaded for adjustment in the opening 14 formed in 50 said head block. The outer end of the shank

has a wheel 15 fixed thereto and provided with peripheral notches 16 for engagement with the spring finger 17 fixed to the outer side of the head block. Obviously the finger 17 when engaged in a notch of the wheel will 55 hold the needle valve in adjusted position. Leading from the chamber 11 is a duct 18, the purpose of which will be later explained.

A flanged bushing 19 is employed and is fitted in the upper end of the feed cylinder 60 20, said bushing having an annular groove 21 formed in its upper surface which communicates with the feed cylinder through ducts 22. A rotating valve 23 is fitted in the socket 24 of the head block and has a port 65 25 which can be placed in registration with the passageway 26 leading from the groove 21 in order that fluid may be exhausted through the valve to atmosphere.

Movable in the feed cylinder 20 is the 70 packed head 27 of the feed piston 28, said piston being hollow and is adapted to extend through the plug 29 fixed in the lower end of the feed cylinder, as customary. To exhaust any pressure fluid which might leak by 75 the head 27 the cylinder has a perforation 30 formed therein.

Briefly the operation is as follows:

Assuming that the needle valve is unseated and pressure fluid from the line enters the 80 passages 8 and 9, around the needle valve, through the duct 18 to the annular groove 21 and from thence through the ducts 22 to act upon the head 27, which causes the feed piston to move outwardly without resistance 85 owing to the presence of the perforation 30. It is desirable at times to vary the pressure upon the feed piston according to the material being drilled, such for instance hard or soft rock. This is readily accomplished upon 90 adjusting the needle valve away from its seat to increase the pressure by permitting a greater flow of pressure fluid from the duct 8 to the duct 18 and toward its seat for decreasing pressure by restricting the flow of 95 pressure fluid from the duct 8 to the duct 18. The valve 23, when the device is in operation, is closed to permit fluid pressure to build up in the chamber behind the feed piston 27. When this valve is opened the 100

feed cylinder is exhausted to atmosphere and the piston may then be retracted. The needle valve can obviously be held in adjusted positions by the spring finger 17.

- 5 In the modified form of the invention the passage 8 does not have associated therewith the needle valve to control the flow of pressure fluid from the throttle valve to the annular groove 21 to act upon the head 27.
- 10 The head block in this instance has a passage 31 leading from the annular groove 21 to the chamber 32 in which operates the needle valve 33 for controlling the passage of fluid from the passage 31 to the passage 34 which leads to the rotating valve 35. The construction of the needle valve is identical to that of the preferred form of the invention.

Obviously when pressure fluid enters the chamber 36 in the bushing 19 it will act upon the feed piston to move the same outwardly from the feed cylinder. The quantity of pressure fluid released from the feed cylinder can be conveniently regulated upon adjusting the needle valve 33 to control the flow of fluid through the passages 31 and 34. The adjustment of the needle valve 33 in this form of the invention, in effect, restricts the egress of fluid from the feed cylinder. The wider this valve is opened the less will be the pressure in the cylinder and vice versa. It will be observed that the modified form of the invention has parts identical to those of the preferred form, differing therefrom by placing the needle valve so as to control the egress of fluid from the feed cylinder instead of the ingress thereto.

What is claimed is:—

1. In a pneumatic tool a cylinder having a hammer piston reciprocable therein, a feed cylinder having a feed piston reciprocable therein, a head block disposed between said cylinders, a bushing fitted in said feed cylinder, there being an annular groove in said bushing, there being a passage communicating said groove with the interior of said feed cylinder, there being a fluid pressure inlet and a fluid pressure outlet, in said head block, there being a passage-way in said head block communicating said inlet with said groove and a second passage-way in said head block communicating said outlet with said groove, and means for restricting the flow of pressure fluid through one of said passages.
- 55 2. In a pneumatic tool a cylinder having a hammer piston reciprocable therein, a feed cylinder having a feed piston reciprocable therein, a head block disposed between said cylinders, a bushing fitted in said feed cylinder, there being an annular groove in said bushing, there being a passage communicating said groove with the interior of said feed cylinder, there being a fluid pressure inlet and a fluid pressure outlet, in said head block, there being a passage-way in said head block

communicating said inlet with said groove and a second passage-way in said head block communicating said outlet with said groove, and means for restricting the flow of pressure fluid through the passage which communicates said inlet with said groove.

3. In a pneumatic tool a cylinder having a hammer piston reciprocable therein, a feed cylinder having a feed piston reciprocable therein, a head block disposed between said cylinders, a bushing fitted in said feed cylinder, there being an annular groove in said bushing, there being a passage communicating said groove with the interior of said feed cylinder, there being a fluid pressure inlet and a fluid pressure outlet, in said head block, there being a passage-way in said head block communicating said inlet with said groove and a second passage-way in said head block communicating said outlet with said groove, and means for restricting the flow of pressure fluid through the passage which communicates said outlet with said groove.

In testimony whereof I affix my signature. 90
LOUIS W. GREVE.
